UNITED STATES PATENT OFFICE.

FRANK LA BARE, OF OWATONNA, MINNESOTA, ASSIGNOR, BY MESNE ASSIGNMENTS, TO THE CREAMERY PACKAGE MFG. COMPANY, OF CHICAGO, ILLINOIS, A CORPORATION OF ILLINOIS.

COMBINED CHURN AND BUTTER-WORKER.

1,183,884.

Specification of Letters Patent.

Patented May 23, 1916.

Application filed March 6, 1914. Serial No. 822,856.

To all whom it may concern:

Be it known that I, FRANK LA BARE, of Owatonna, Steele county, Minnesota, have invented certain new and useful Improvements in Combined Churns and Butter-Workers, of which the following is a specification.

This invention relates to improvements in combined churning and butter workers, and particularly to that type of machine in which a pair of butter working rolls is arranged within a revoluble drum and are held, during the butter working operation, in a stationary position, while each of said rolls is rotated inwardly toward the other upon its own axis and the butter which is carried up by the wall of the drum and flights thereon is dropped onto the rolls and is passed between them, this operation being repeated as often as necessary until the butter is completely worked.

My present invention relates particularly to improvements in the combined churn and butter worker described and claimed in Letters Patent of the United States No. 866,038, issued to me September 17, 1907.

The object of my present invention is to provide means for causing the butter, after it has been worked, to pile up in the vicinity 30 of the door opening, so that it can be easily removed from the combined churn and butter worker.

The invention consists generally in the constructions and combinations hereinafter described and particularly pointed out in the claims.

In the accompanying drawings forming part of this specification Figure 1 is a transverse vertical section of a combined churn and butter worker embodying my invention. Fig. 2 is a longitudinal horizontal section of the same. Fig. 3 is a side elevation of a portion of the frame and the forward end of a churn with my improvement applied thereto. Fig. 4 is an end elevation of the mechanism shown in Fig. 3 with the driving pulley omitted. Figs. 5, 6, 7 and 8 are details.

In the drawings, 4 represents the drum 50 of the machine, which may be of any suitable length and diameter and which is provided upon its interior near the circumferential wall thereof, with the flights or shelves 5. I have shown three of these

flights of ordinary width and construction, but any desired number thereof may be employed. The churn drum is supported in a suitable frame 1, of any suitable form and construction. It may be substantially that shown in my former patent above referred to. It is provided with suitable means, whereby when the machine is operated for churning the sectional heads 14, the cross heads 11 and the rolls 10 may be all locked to and rotated with the drum. I prefer in this construction to employ also the rectangular bars 31 mounted upon gudgeons, capable of rotating freely upon their axes. These bars are usually designated "roller shelves" and they are mounted loosely in the cross heads 11, and the purpose is to permit said bars to turn upon their axes in case any butter lodges upon one corner or edge thereof, thereby causing said butter to fall off from these bars, either by falling back into the churn or falling forward into the butter working rolls.

Butter working rolls 10 are mounted in the cross heads 11 and their gudgeons 12 extend through the sectional head 14, at one end of the drum and they are provided with suitable means by which said rolls may be driven, preferably as set forth in my Patent No. 866,038, hereinbefore referred to.

The ends of the drum are preferably supported in bearings upon the frame of the machine by suitable spiders 7 provided with hollow gudgeons 8 that are rotatably arranged in bearings in the frame of the machine. The forward end of the drum is preferably provided with a ring gear 9 engaged by a pinion 13 on a dog 13', and this pinion may be driven from the driving pulley 17 at either a fast or a slow speed, thereby permitting the churn drum to be revolved rapidly during the churning operation and to be revolved slowly during the butter working operation. The driving pulley 17 is loosely mounted upon the shaft 13'. The pulley may be connected with said shaft 13' by a suitable clutch device. A sleeve 20 has secured to it a suitable pinion 21. The pinion 13 may be driven directly from the sleeve 20 by means of the sliding sleeve 23 splined to the shaft 13' or indirectly through the back gears 21, 24, 25 and 26, in a manner well understood in this class of machines. A pinion 27 may be caused to

rotate with the gear 24, and this pinion, through the gears 28 and 29, is arranged to rotate a shaft 32 carrying a pinion 33 that drives the roll gears 34 and 35. A tubular 5 shaft 36 is arranged within the gudgeon 8 of the spider 7 and forms a bearing for the shaft 32, which carries at its forward end the gear 29 and at its rear end the pinion 33 hereinbefore referred to. Mounted upon 10 the forward end of the gudgeon 8 is a sprocket pinion 37 and splined upon the forward end of the tubular shaft 36 is a disk 38 (see Fig. 5), having the peripheral notches 39. This disk carries a pin 40 normally in engagement with a hole in the pinion 37 and adapted when the disk is moved toward the gudgeon 8 to engage a hole in the end of the gudgeon and thereby to lock the tubular shaft, the pinion 37, and 15 the gudgeon 8 together, so as to cause them to rotate simultaneously. When the disk is moved in the opposite direction, into the position shown in Fig. 8, the notches 39 in said disk engage inwardly extending lugs 20 41 upon the arm 42 forming a part of the frame of the machine. A lever 43 is provided for moving said disk 38 longitudinally upon the tubular shaft 36. When the parts are in the position shown in Fig. 8 25 30 the cross heads carrying the rolls, and consequently the rolls, will be held in a stationary position, and preferably with the cross heads 11 inclined substantially as shown in Fig. 1 of the drawings. When the device is 35 to be used for churning the disk 38 is moved in the opposite direction by the lever 43, and the tubular shaft, the disk 38, and the sprocket 37 are all locked to the gudgeon 8 and rotate with the drum. A chain belt 40 45 passes around the pinion 37 and drives a shaft 46 that runs lengthwise of the machine near the bottom of the frame (see Fig. 4). This shaft has a suitable connection (not shown) with a tubular shaft carrying the 45 50 cross head at the opposite end of the machine.

The churn body is provided with a suitable door opening 15 at one wall thereof and this opening is provided with a suitable 55 door 16. When the door is closed the churn body is rendered cream tight, and when it is opened the butter may be removed through the door opening.

The cross heads 11, the roller shelves 31 55 mounted loosely therein, and the rolls 10 having their gudgeons passing through the said cross heads and through the sectional heads 14, are capable of being turned and locked by the means described with the plane 60 of the rolls at any desired angle. In ordinary practice during the butter working operation the rolls will be in substantially the position shown in Fig. 1 of the drawing, with the plane thereof inclined toward the 65 door opening, and when the butter working

operation is completed the drum will be stopped with the broad flight 18 in the position shown in Fig. 1. In this position the flight 18 substantially fills the space between the cross heads and roller shelves and the 70 inner wall of the drum, thereby forming a jacket or hopper to hold the butter in position to be conveniently removed through the door opening.

When the cross heads 11 are in the position shown in the drawing there is an inclined and practically level surface consisting of the tops of the roller shelves 21, the rolls 10 and the shelf 18. The butter may all be brought into that section of the drum 75 which contains the door 16, and then by having the broad shelf 18 in the position shown in the drawing with the cross head 11 set in the position also shown in the drawing, a large hopper is formed immediately by the door opening in which all of the butter can be gathered in position to be quickly removed through said door opening.

I also find that by locking the rolls and drum together during the churning operation with the broad flight parallel with the plane of the rolls as shown in Fig. 1 of the drawings, a partition is formed extending more than half way across the drum and this partition causes a greater concussion in 85 the cream and thereby a quicker churning is obtained.

The details of the construction may be varied in many particulars without departing from my invention.

I claim as my invention:

1. In a combined churn and butter worker, the combination, with a revoluble drum, having a door opening in the peripheral wall thereof, of a pair of butter working rolls arranged in said drum, cross heads supporting said rolls parallel with each other, means for rotating the drum while the cross heads remain in a stationary position with the drum rotating about said cross heads and the rolls supported thereby, means for rotating the rolls upon their own axes, means for locking the said supporting cross heads in a stationary position with the plane of the rolls at any desired angle, flights upon the interior of said drum, the width of the flight which is below the door opening being substantially equal to the distance between the ends of the cross heads and the periphery of the drum, whereby 115 when said cross heads are locked, said last named flight may by a revolution of the drum be brought into a position to substantially fill the space between the cross heads and the wall of the drum and form a pocket 120 or hopper on which the butter will rest in convenient position to be removed from the drum through the door opening, substantially as described.

2. In a combined churn and butter 125

worker, the combination, with a revoluble drum, having a door opening in the peripheral wall thereof, of a pair of butter working rolls arranged in said drum, cross heads supporting said rolls below the axes of the drum and parallel with each other, means for rotating the drum while the cross heads remain in a stationary position with the drum rotating about said cross heads and the rolls supported thereby, means for rotating the rolls upon their own axes, means for locking the said supporting cross heads in a stationary position with the plane of the rolls at any desired angle, flights upon the interior of said drum, the width of the flight which is below the door opening being substantially equal to the distance between the ends of the cross heads and the periphery of the drum, whereby when said cross heads are locked, the last named flight 20 may by a revolution of the drum be brought into a position to substantially fill the space between the cross heads and the wall of the drum, and form a pocket or hopper on which the butter will rest in a convenient 25 position to be removed through the door opening, substantially as described.

In witness whereof, I have hereunto set my hand this 7th day of February, 1914.

FRANK LA BARE.
